COIN-FREED APPARATUS

Application filed March 24, 1931, Serial No. 524,902, and in Great Britain March 20, 1930.

The present invention relates to coin-freed apparatus of the kind permitting of the purchase outright or the hire of an article such as a book.

5 In apparatus of this character heretofore proposed it has been suggested to operate the apparatus by means of two or more coins one of which is returned to the exterior of the apparatus if the article is replaced in the 10 apparatus.

The chief object of the present invention is to provide an improved coin-freed apparatus particularly adapted for the alternative hire or purchase of an article which is of simple 15 construction.

Further objects of the present invention are to provide improved coin-freed apparatus for the alternative hire or purchase of an article which it is impossible to operate except in the 20 manner intended which is free from external protuberances which occupies the minimum of space and which is devoid of delicately adjusted parts such as balance rods and mechanism operated by the weight of the coins inserted with the result that the improved apparatus is particularly suitable for mounting on vehicles such as trains motor road coaches and the like.

In order that the present invention may be 30 more clearly understood and readily carried into effect by those skilled in the art to which it appertains reference may now be had to the accompanying drawings which illustrate by way of example one form of apparatus embodying the invention.

In the drawings:—

Fig. 1 is a front elevational view of the improved apparatus;

40 Fig. 2 is a cross sectional view on the line 2—2 of Fig. 1 with certain parts omitted;

Fig. 3 is a side elevational view of the apparatus viewed from the right as shown in Fig. 1 certain parts being shown in cross section;

45 Fig. 4 is a front elevational view of the apparatus shown in Fig. 1 with certain parts omitted and with part of the front wall of the container or receptacle for the article removed;

50 Fig. 5 is a cross sectional view on the line 5—5 of Fig. 1; and

Fig. 6 is a cross sectional view on the line 6—6 of Fig. 4.

In the drawings there is illustrated an apparatus intended for the alternative sale or hire of an article such as a book the apparatus 55 being adapted for operation by the insertion therein of four coins, namely three pennies being the fee for the hire of the article and one shilling which is a security coin returnable to the hirer upon the return of the article 60 to the apparatus and closure of the article container or receptacle. As shown the apparatus comprises what may be termed a frame element 1 which may be formed as an integral or unitary structure and is preferably made 65 of metal. This frame element may conveniently be divided by partition walls 2 and 3 to provide three compartments the lowermost of which designated generally by the reference numeral 5 is again divided by partitions 70 or walls 6 to provide three additional compartments.

In the upper compartment 7 there is housed a container or receptacle 8 for an article such as a book whilst the compartment 9 serves 75 to house the working parts of the apparatus. A backing plate (not shown) normally extends over the whole of the rear of the apparatus thereby closing the compartment 9 and at the same time affording means whereby the apparatus may be secured in any position. Conveniently the backing plate may be fixed in the position the apparatus is to occupy the frame element being adapted to be detachably attached thereto and to be 80 locked in position by the means for locking the coin receptacle (hereinafter described) in position.

As shown the receptacle 8 is pivoted or hinged at 10 to the frame 1 in such wise that 90 when released it is capable of being rocked to a position as indicated in dot and pick lines in Fig. 2 such that the article therewithin may be removed for example through the open end 11. If desired a finger hole or the like 12 may be provided at the lower part of the receptacle 8 to facilitate removal of the article. The receptacle 8 may also be provided with a transparent window or windows 12a to enable a portion of the article to be 100

viewed. In the case of a book the title may be observable through the window or windows.

At the rear of the receptacle 8 there are provided catches 13 forming portions of the locking devices which may conveniently be mounted for vertical sliding movement in elements 14 on the rear wall of the receptacle 8 and are upwardly biased by springs such as shown at 15 also mounted on the rear wall of the receptacle. The catches are adapted normally to project through apertures 16 in the partition wall 2 and engage with an element or elements 17 constituting other portions of the locking devices to hold the receptacle 8 in the closed position as shown in full lines in Fig. 2.

There is also mounted at the rear of the receptacle 8 means designated generally by the reference 18 acting normally to prevent closure of the article container or receptacle 8 but which is adapted to be rendered inoperative by the insertion of the article thereinto to permit closure thereof. Such means may conveniently comprise a pivoted element 19 having a portion 20 within the receptacle and a portion 21 adapted to enter an aperture 22 in the partition wall 2 as shown when the article is within the receptacle. The element 19 is preferably controlled by a spring in such wise that when the receptacle 8 is rocked about its pivot 10 and the article removed therefrom the portion 21 assumes a position as shown in dotted lines in Fig. 2 such that it will not enter the aperture 22 but fouls the partition 2 if an attempt is made to close the receptacle. On the other hand when the article is inserted into the receptacle 8 its lower end contacts with the portion 20 of element 19 and moves it to a position so that the portion 21 will enter the aperture 22 thereby allowing the receptacle to be locked in the closed position as shown in full lines in Fig. 2.

For the purpose of guiding the coins necessary for operation of the apparatus coin slots or guides may conveniently be formed on or attached to the partition 2 and in the case of the particular apparatus shown the partition 2 is shaped or formed to provide slots 23 appropriate in size and number to the coins to be used and guard strips 24 are provided to prevent the coins becoming dislodged from the slots 23. The slots or guides 23 extend from the top of the apparatus where the coins are adapted to be inserted to a coin receptacle 25 in the case of all the coins except the security coin or coins the one or more slots for which communicate with a coin return chamber 26.

Any convenient means may be provided for retaining the security coin in such a position as to permit of its being returned to the exterior of the apparatus upon correct operation of the apparatus and as shown this

comprises a coin retaining device 27 having a horizontal limb 28 which traverses the security coin slot at a convenient point in its length and is adapted to be operated by opening and closing of the receptacle 8. For this purpose the limb 28 is slotted to an extent to permit passage of the coin when it is in certain positions and the receptacle 8 is provided with means for actuating the device 27. With the receptacle in the position shown in full lines in Fig. 2 the device 27 is retained by the receptacle 8 in such a position that the slot in limb 28 coincides with the security coin slot but it will be appreciated that when the receptacle is moved to the position shown in dot or pick lines by being rocked about its pivot or hinge 10 as previously explained the device 27 follows the movement of the receptacle 8—either by virtue of its resilient nature or under the action of a spring—and the slot in the limb 28 is moved out of coincidence with the security coin guide or slot whereby the coin in the slot is retained by the limb 28. However, upon the return of the article to the receptacle 8 and closure thereof the device 27 is operated to bring the slot in the limb 28 into coincidence with the coin slot or guide thereby permitting the coin to fall into the chamber 26.

The coins required for operation of the apparatus are inserted into the coin slots or guides 23 through suitable slots in the upper wall of the frame of the apparatus down which they fall under gravity until arrested by the portions 13 of the locking devices which project across the coin slots when the receptacle is in the closed position as previously described. The movement of the coins necessary to cause release of the locking devices may conveniently be obtained by acting upon the coins simultaneously by means of projections 29 formed on or attached to a cover or flap 30 hinged or pivoted to the frame at 31 which projections enter the coin slots or guides when the cover is closed as shown in Fig. 3 and press downwardly upon the coins thereby moving them to an extent sufficient to cause such downward movement of the portions 13 of the locking devices against the action of their springs 15 as is necessary to move them out of engagement with the element 17 thereby releasing the receptacle 8 which turns or rocks about its pivot 10 either under the action of gravity or under the action of a spring to permit access thereto. This turning or rocking movement of the receptacle is assisted in the apparatus shown by reaction between downwardly pressed coins and the inclined extremities of the portions 13 shown in the drawings. Upon removal of the portions 13 of the locking devices from the coin slots or guides 23 all the coins except the security coin which is arrested by the device 27 as

previously explained continue their downward movement to the coin receptacle 25.

The cover or flap 30 may conveniently be provided with means whereby it is prevented from being moved to uncover the coin slots unless the receptacle 8 is closed and means may also be provided to prevent the receptacle 8 being moved to such a position as to permit access to the article when the cover or flap 30 is in the open position thereby preventing operation of the locking devices by means such as a knife or knives the insertion of which in the coin slots will not allow the cover or flap to be closed. The latter means may take the form of a curved lip 32 resiliently mounted upon the top of the frame 1 and cooperating with a flattened or cut away portion of the hinge pin 30a in such wise that the lip 32 is pressed into a slot or groove 33 formed or provided on the upper edge of the receptacle 8 when the flap is open but springs out of said slot when the cover or flap is closed. In addition the lip may be used to prevent the coin slots being moved when the receptacle 8 is open by contacting at such time, or when an attempt is made to uncover the slots, with the rear wall of the receptacle or with a projection on lip thereon.

Preferably means such as stops 34 are provided to engage the rear wall of the receptacle 8 to permit opening of the receptacle to an extent just sufficient to permit removal of the article therefrom and means such as stop 35 may also be provided to prevent undue closing thereof.

To provide a record of the number of times the receptacle 8 is opened a counter 36 of any known constructional form may be provided which is visible through a window 37. The counter may be operated through suitable linkage designated generally by the reference numeral 38 but which does not require to be specifically described.

To facilitate removal of coins from the coin receptacle the base of the frame may be apertured at 39 and the upper side walls of the receptacle 25 itself may be recessed as shown by the dot and pick lines 40 in Fig. 1 so that as the receptacle is removed by movement to the right as shown in Fig. 1 it may at the same time be given a slight upward tilt thereby causing the coins to be ejected through an aperture 41 in the corner of the receptacle and through the aperture 39 into a receptacle held beneath the apparatus.

Although in the foregoing there has been described one embodiment of apparatus according to the invention various modifications thereof may be made therein without departing from the spirit and scope of the present invention. For example instead of the article container or receptacle being bodily movable to permit removal of the article therefrom it may actually be a part of the frame and access may be had thereto through

a hinged door or flap upon which portions of the locking devices are mounted closure of the flap to operate mechanism for returning the security coin being controlled by means operated by the weight of the article to prevent closure of the container without first replacing the article. In a modified form of apparatus of this character according to the invention the container may have a false bottom upon which the book or the like rests and which may be spring urged to assume a definite position when the book is removed from the container but which assumes a position such that its edge will enter a slot or behind a projection on the flap or door of the container when the book is placed in the compartment. The false bottom may be caused to assume the latter position under the weight of the book or by making the compartment of a height or width substantially the same as that of the book and may be divided into a number of separate elements or fingers as a guard against attempted closing of the container or compartment and unauthorized obtaining of the security coin without replacing the book.

In close proximity to the container there may be provided a further container or compartment housing the locking devices and preferably also serving as a receptacle for the coins inserted into the apparatus and the door or flap is extended to cover the container or compartment containing the locking devices which container or compartment may conveniently be positioned below the container or compartment for the book.

The flap or door is provided with slots of such a size as to pass the coins by which the apparatus is to be operated and a coin holder is mounted upon the face of the door flap in registry with each aperture or slot the holders being notched for engagement with ratchet catches suitably mounted within the container or compartment for the coins—for example upon the back wall thereof—when the door or flap is closed. In the closed position the holders project through corresponding apertures or slots in the front wall of the last mentioned container or compartment.

Mounted upon the door or flap in proximity to the apertures or slots for the coins is a hinged cover provided with projections registering with the said apertures or slots for pressing the coins thereinto and operating the aforesaid ratchet catches. The cover is also preferably provided with means such that the door or flap can only be opened to permit access to the article when it is in the closed position i. e. flush with the surface of the flap or door. Such means may take the form of an element projecting from the front face of the container or compartment for the coins adapted to project through an aperture or slot in the door or flap when closed and co-

operate with the hinge of the cover. Preferably the element is provided with a slot of such form that the cover can be moved to open position only when the door or flap is properly closed.

- 5 The coins when pressed into the apertures or slots above described by the projections on the cover thrust the ratchet catches out of engagement with the notches on the coin holders thereby unlocking the flap or door which may now be opened to permit removal of the book. If desired means may be provided to prevent the flap or door being opened roughly and to provide additional security.
- 10 15 For this purpose a pivoted catch may be provided and so arranged—as by being pivoted slightly to the rear of the surface of the front face of the door or flap—that it cannot be depressed to permit full opening of the flap or door until the door has been opened a short distance.

Upon opening of the door or flap the holders of the coins being attached to the door or flap are withdrawn with it and the coins fall 25 into the bottom of the container or compartment with the exception of one—the security coin—which only falls to a point just above a delivery slot where it is held by a finger.

30 The book can now be removed and by so doing the false bottom rises slightly under the influence of its spring loading thereby moving its edge into a position such that it will not enter the aforesaid slot or behind the aforesaid projection and consequently the flap or door cannot be closed.

When the book is returned to the container the false bottom is moved to enter the slot or behind the projection on the flap or door and the latter can be closed. When this is 40 done the ratchet catches re-engage the notches on the coin holders and re-lock the flap.

45 At the same time an inward forked projection on the door or flap co-acts with the finger retaining the security coin or with mechanism associated therewith to move the finger to release the coin which is returned to the hirer via the delivery slot and the other coins are retained in the apparatus as a 50 charge for the hiring of the book. Preferably the finger or its associated mechanism is bevelled—for example to V form—to prevent unauthorized operation and a guard may be placed over the point of the bevel to prevent operation of the coin return mechanism by anything except a forked rod.

55 What I claim is:—

- 60 1. Coin-free apparatus for the alternative sale or hire of an article comprising in combination a receptacle for said article, a plurality of coin slots, a coin receptacle, locking devices portions of which are associated with said article receptacle and project into said coin slots to arrest coins inserted in said slots 65 as they move therealong to said coin recep-

tacle, a cover hingedly mounted adjacent said coin slots, projections on said cover adapted when said cover is closed to enter said slots and by simultaneous engagement with coins therein to cause said coins to release said locking devices and permit opening of said article receptacle and removal of the article therefrom, and mechanism for returning at least one of said coins to the exterior of the apparatus upon the return of the article to said receptacle and closure thereof.

70 2. Coin-free apparatus as claimed in claim 1 comprising cooperative means on said cover and said article receptacle to prevent the cover being moved to permit access to said coin slots when said article receptacle is open.

75 3. Coin-free apparatus as claimed in claim 1 comprising cooperative means on said cover and said article receptacle to prevent opening of said article receptacle when the cover is in a position to permit insertion of coins in said coin slots.

80 4. Coin-free apparatus as claimed in claim 1 comprising a resilient lip on the frame of the apparatus adjacent said article receptacle and means on said cover for cooperation with said lip substantially as and for the purposes specified.

85 5. Coin-free apparatus for the alternative sale or hire of an article comprising in combination, a hinged receptacle for said article, a plurality of coin slots, a coin receptacle communicating with at least one of said coin slots, catches on said article receptacle forming part of locking devices therefor and which in the closed position of said article receptacle project into said coin slots, a cover hinged to said apparatus adjacent the entrance to said coin slots, projections on said cover adapted to enter said coin slots when said cover is in one position and cause coins therein to act simultaneously on said catches to release said article receptacle and permit withdrawal of the article contained therein, a movable device projecting into one of said coin slots and operating upon opening movement of said article receptacle to retain one of said coins in a predetermined position, said device being further operated upon closure of said article receptacle to release the coin previously retained and permit its return to the exterior of the apparatus.

90 6. Coin-free apparatus as claimed in claim 5 comprising cooperative means on said cover and said article receptacle to prevent the cover being moved to permit access to said coin slots when said article receptacle is open.

95 7. Coin-free apparatus as claimed in claim 5 comprising cooperative means on said cover and said article receptacle to prevent opening of said article receptacle when the cover is in a position to permit insertion of coins in said coin slots.

100 8. Coin-free apparatus as claimed in claim 5 comprising a resilient lip on the

frame of the apparatus adjacent said article receptacle and means on said cover for co-operation with said lip substantially as and for the purposes specified.

- 5 9. A coin-free apparatus as claimed in claim 5 including an aperture on the frame and a spring biased element mounted upon said article receptacle and having a portion adapted to enter said aperture when an article of the correct dimensions is positioned in said article receptacle and thereby permit closure of said article receptacle, said element being moved under its bias to prevent said portion entering said aperture and consequently to prevent closure of said article receptacle when no article is contained therein or when said article receptacle contains an article of incorrect dimensions.
- 10 10. Coin-free apparatus for the alternative sale or hire of an article comprising in combination, a horizontally hinged receptacle for said article, a plurality of slots for coins fixed on the frame of said apparatus, a coin receptacle communicating with at least one of said coin slots, locking devices including a resilient portion on said article receptacle and a cooperating element associated with each said coin slot, a cover hinged to said apparatus adjacent the entrance to said coin slots, projections on said cover adapted in one position of said cover to enter said coin slots and act simultaneously and directly on coins whose movement along said slots to said coin receptacle is normally retarded by the resilient portions of said locking devices to cause said coins to unlock said locking devices and permit opening of said article receptacle by movement about its hinge, and a coin retaining device which upon opening of said article receptacle arrests one of said coins in a predetermined position, said last mentioned coin being released for movement to the exterior of the apparatus upon closure of said article receptacle.
- 15 45 In testimony whereof I have signed my name to this specification.

VERNON MERIVALE.
